Otis Tufts
Letters Patent

The schedule referred to in these Letters Patent and making part of the same containing a description in the words of the said Otis Tufts himself of his improvements in the "Power Printing Press".
To all persons to whom these presents shall come. Otis Tufts of Boston in the County of Suffolk and State of Massachusetts doth greet. Be it known that the said Otis Tufts have invented made and applied to side certain improvements of machinery for the purpose of printing paper or other substances generally used for receiving impressions from types. Which inventions when all combined together with other parts constitute and are commonly known by the appellation of a "Power Printing Press". The descriptive arrangement and use of the several parts I have fully described and set forth in the following word and annexed drawings which taken in connection form my specification. The main or principle difference between this Power Press and others now in use consists in supplying it with paper to be printed from one side of the forme by using two fistholt one of which is under the operation of an impression from the platten while the sheet of paper last printed is being removed from the second fistholt and another sheet supplied. As soon as the fistholt first mentioned has received an impression from the types it is withdrawn by the operation of the machinery from between the platten and forme and the second fistholt caused to pass in between the platten and forme in time to be acted on in its turn. So on in succession each passes out from between the platten and forme with its printed sheet while the other with the sheet to be printed is made to pass in between the platten and forme as so frequently the fly-wheel of the press constructed in the usual form and suitable size being attached to the driving shaft. The shaft is operated on and caused to turn round by man

Drawing in full face

not labor required on a creek, or by means of a steam engine, horse or water power, acting on a drum or pulley affixed in its side. The shaft D. revolves at one end in a composition or otherwise suitable metal box or attached to the extremity of the shaft D. of the casting frame D. E. The opposite end rests on the periphery of a friction wheel E. in the shaft D. upon a pinion C. is fastened in the driving shaft B. whose teeth act in the interteeth or links of a chain belt D. passing around it and the cogged wheel C. in the main shaft F. The frame D. B. of the pump is of cast iron but may be constructed of wood or other suitable material shaped and formed as seen in the drawings or otherwise shaped and formed to answer the intended purpose of supporting the bed platform and machinery for the operations connected with the same. The main shaft F. has journals at each extremity consisting in composition or other suitable metal boxes L. L. attached to the upright posts G. G. of the frame work D. B. as seen and represented in the drawings. To the centre of the main shaft F. is secured in a proper manner a case G. consisting of the form seen in Figs. 2, 5. having a roller in. in its small end for the purpose of diminishing the friction at the time of the impression and which also turns round a certain distance at every revolution of the case. This presenting a new surface for the roll in the end of the piston to move over by which the abrasion of the roll is greatly diminished. The opposite end of the case G. is a cowl. the centre being in the centre of the shaft. During the revolution of the last-mentioned part on or against the roller in the end of the piston. It produces no motion of the piston in either backward or forward but as soon as the side of the case comes in contact with the roll it passes it forward until it arrives at the opposite end of the roll in the case when the impression ceases and the opposite side of the case permits the piston to move until the roll in the end of the piston meets the cowl surface of the cylinder.

of the same and again becomes stationary during the revolution of the said surface. The pitman H. is supported during its back and forth movements by the upright vibrators 10. (of the form seen in Fig. 8.) to which it is attached at the top by a joint.

The lower end of the upright 10. revolves on bearings 1. 1. attached to a bar or connecting piece of iron I. of the opposite sides of the frame 11. 11. The opposite end of the pitman H. rests on the centre pin of the toggle joints 10. 10. and causes them to be brought together or on a straight line with each other by the centre pin bearing against the side of a vertical space cast in the lower side of the pitman as more clearly represented in Fig. 3. That part of the pitman from where it rests on the centre pin of the toggles (when in action) to the extreme end of the same is formed flat on the lower side so that when the pitman is raised this part offering no projections but a plain surface throughout its length to the centre pin of the toggles moves over the said centre pin without producing any back or forth motion of the joints.

The lower end of the toggle 10. rests on a pin in steps in the large iron cross beam 11. The upper end of the toggle 10. plays on a similar pin or step in the lower side of the bed 11. The platten O has a large iron beam M. cast or attached to its upper side. the ends 12. 12. projecting over the sides of the frame 11. 11. Strong enough iron bolts O. O. having keys and nuts at their tops to admit of their being secured to the projecting ends of the cross beam of the platten, pass downward through guide keys in a vertical direction and are secured by heads at their opposite ends to the cross beam 11. The platten O and beam M. and connecting bolts O. O. are balanced by a counterpoise weight P. attached to a lower, formed of projections from a horizontal shaft P. suspended at its ends by journals and bays at the ends to the opposite sides of the frame 11. 11. the shaft carrying as the fulcrum of the lower. On the extremity of the horizontal

horizontal shaft γ is fixed a cam projecting iron of whose end is hollowed out as a step to receive and support a small pitman π . The upper end of the small pitman π terminates in a small ball which turns in a hemispherical socket in the lower side of the head of the upright bolt α . The fly wheel being set in motion turns the driving shaft B . Then by causing the cogged pinion c to turn round by the intervention of the chain belt, the cogged wheel e in the main shaft E . The case G revolving with the shaft acts in the pitman which it pushes forward communicating the motion to the toggles, bringing them in a straight line at the same time drawing downwards the platten on the sheet between it and the form of type, thus giving the impression. On the main shaft B is fixed the grooved case R , for the purpose of operating on the friction to produce their rectilinear motion in and out from between the platten and form. After the impression has taken place the toggles are brought back as the platten rises by a cam A on the shaft (of the form seen in the drawing, or otherwise shaped and formed to answer the purpose) as the shaft revolves this cam presses down an arm or strut B attached to the upright α . The peculiar object of this cam is to always ensure the back motion of the toggles, which as they are brought in a straight line with each other are sometimes liable in printing suffer to remain so and not depart from it. A small iron or steel roller travelling on a rail in the end of the bent bar B travels in the groove of the cam A . The bar B at its other extremity is attached to the upright vibrator I by a pin at a sufficient distance from its foot or centre of motion so as to form a joint to admit the movements to and fro of the vibrator. The vibrator I is formed as represented in Fig. 3, open in the centre to permit the passage through and action of the pitman and upright, &c. At its foot it moves on suitable bearings

bearings similar to the upright Jc . The top of this vibrator is attached by a joint to the connecting rod I' whose opposite end is attached by another joint to the projection q' of the bed-hot carriage U . The first hot carriage U is composed of two side pieces s.t. united together at each end by a brace or iron bar u.u. The sides of the first hot carriage are mainly fitted to traverse in rails v.v. similar to the bed and rail way of the common hand printing press. The rails being of a proper length and size to ensure the required motion and out from the frames. The first hot carriage are plain rectangular iron frames as seen in Fig. 9. with wide ears or projections w.w. of suitable length on each end which serve to sustain them with the sheet on the grooves through which they move. They are covered and prepared in the usual way for printing, with interstices or spaces cut out for the operation of the type on the paper. The projections before mentioned on the ends of the first hot carriage move back and forth in the grooves x.y. cut in a plate of iron or other metal screwed or other wise properly fixed to the sides of the frame U.U. x.x. is the apparatus for changing the first hot carriage from one of the grooves x.y. to the other as the case may be. The part denominated x is composed of composition or any other suitable metal shaped in the front view as represented in Fig. 6. and more clearly shown in section Fig. 7. It is constituted of a plate b' at top to which is attached a long shank c' whose foot is attached by a joint to a bar d' vibrating on a pin at its opposite end passing into the frame U.U. the main shaft revolves a small arm e' striking against the top of the bar d' moving it downward and the plate b' connected to it. A spring f' operates to draw upward the bar d' when the action of the arm has ceased. A long bar d' vibrates at once on a pin applied to the inside of the frame U.U. the opposite end being attached by a joint to the east iron right beam

8/22/1834 8380X

beam M. The office of this bar is to prevent the lateral presence of the pitman, on the lower toggle joint from changing the wavy beam M from a right line during its perpendicular motions. To the top of the plate B' is screwed or otherwise attached a straight bar c' the lower side of which is intended to form the upper side of a groove E'. The lower part of the groove E' is formed of a bent piece of metal g' attached at its lower end by a joint to the side of a space cut in the plate c' B'. A spring h' bears against the back of the piece g' to press it outwards during its operations. The outer fall of the straight bar c' is in the same plane with the outer face of another straight bar I' screwed or otherwise affixed to the sides of the frame E, E. When the plate B' is raised to the upper groove X, the lower side of the straight bar c' coincides with the upper side of the said groove X.

The spring h' pushing the curved piece of metal g' outwards causes its top to coincide with the lower side of the groove X, so as to produce a continuation of the groove X, ready to receive an ear or projection m' of the fishet. While the plate B' is moving down the straight bar I' causes the curved piece of metal g' to move inwards so as to deposit the ear or projection of the fishet on the upper face of the bar I' which is a continuation of the lower face of the lower groove g'. When the plate B' rises again to receive another fishet the curved part g' by the presence of the spring h' moves outward and receives the fishet from between the plates and former brought out by the fishet ears. It may be described as the process to be which consists of a plain plate of composition or other suitable metal shaped somewhat similar to a bent without the curved piece g' and spring h'. It has a simple groove H' cut in it and is guided in a perpendicular direction during its motion up and down by the circular sleeve L, sliding through a round hole in a piece of iron

or, screwed or otherwise attached to the side of the frame E.

The proper motions and times of ascent and descent are regulated by the form and revolution of the fishet cam W on the main shaft E. A long lever X formed of two projecting bars U, m¹, form a horizontal ^{shaft} supposition by suitable bearings attached to the sides of the frame E. It has a roller turning on a pin at A, and B¹, which roller moves in the grooved surface of the cam W. The opposite arm U' has connected with it by a joint the foot of the upright bar n¹ whose top is attached by a joint to the crank C' of the moveable plate x. The plate x being suffered up so that its groove shall coincide with the long groove X while the part of the cam W from O to P¹ Fig. 6. is operating on the roll in the end m¹ of the bar X, it moves the plate x downward so as to bring the groove in it in a line with the lower groove y, to receive the fishet from the groove x. While the roll moves over the curved surface from q¹ to r¹ the plate x is brought down still further, until it meets the bed of type when the platen operates on the paper in the fishet during which time the roll is moving over the space from r¹ to s¹ which is an arc of a circle the center being in the centre of the main shaft. The supposition having taken place the platen moves a short distance upward to free the fishet in order to clear itself from the paper. The roll then begins to move over the curved surface of the cam from s¹ to t¹ which raises the fishet up to the upper groove x. Through which it is moved by the fishet carriage into the groove in the plate a with the printer sheet to be removed and another sheet substituted. The plate a having received the fishet is raised downwards by the way revolution of the cam and the curved pinion of metal g¹ g² on which the ears of the fishet rest seconda and deposit the fishet on the top of the straight bar l¹ l²; these being a sort of the plate a to plate x, for each ear of the fishet that is a roll in the middle of each of the sides of the frame E. The fishet is then operated on by the fishet carriage and comes in contact with the platen.

8

ten and forms for an inflexion. That part of the fishet carriage which produces the movements back and forth of the fishet in the groove $X.Y.$ is represented at $t' u'$. t' is an upright projecting piece of iron on the top of each side of the fishet carriage. Its office is to push the fishet out from between the platten and form through the groove $X.$ into the groove in the plate a' u' is a small catch vibrating on and connected to the fishet carriage by a joint at u and always pressed upward by a small spring $v.$ When the fishet carriage pushes outward from the platten with a fishet the small catch $u.$ strikes against the under surface of the ear on the lower fishet and is pressed down during its motion under the said surface. As soon as it leaves the surface it flies upward. When the fishet carriage is carried inward the ends of the catches $u' v'$ come in contact with the ears or projections of the fishet thus pushing it through the lower edge of grooves $Y.Y.$ into the groove in the plate a' when it is received and carried downward by the cam $W.$ to receive an inflexion from the platten. Afterwards it is raised by the action of the said cam $W.$ to the upper groove $X.$ The fishet carriage then moving outward the projections $t' t'$ on each of the sides of the carriage strike against the ears of the fishet and push it through the upper groove X into the groove in the plate a' The above arrangement of the machinery is considered fully sufficient for the operation of the fishets but to guard against any accident which might happen by the carriage $t' t'$ catching against and lifting the ear of the fishet during its onward movement two small pieces of iron $u' v'$ are so hinged at a middle corner of each that the action of gravity will cause them always to stand outward to prevent the fishet ear from rising. The ear during its downward motion presses the small catches $u' v'$ into the socket or space in the plate of iron in which the groove $X.Y.$ run out as seen in Fig. 6, but as soon as the fishet is deposited on the lower edge of the lower groove the small catches are released and

fly outward, thus rendering it impossible for the curved piece g' to move the fistet so as to prevent it being passed through the lower sett of grooves g, g' . Furthermore should the fistet of the carriage has left it on the top of the curved pieces of metal g, g' by a fall of the machinery or any other cause, slide forward in the upper groove x , there is danger when the plate b goes down, of the ear of the fistet being injured. In order to prevent an occurrence of this nature a small a small spring $20'$ is affixed to either the upper or lower side of the end of the groove so that when the ear of the fistet moves through the groove it shall pass over the surface of the spring and press it into a space adapted to receive it. As soon as the ear leaves the spring, it flies outward thus effectually closing the end of the groove against a receding motion of the fistet. The grooved cam $N.$ is so formed and placed on the main shaft that while the roll on the end of the bar 25 is moving from a''' to b''' Fig. 5. it produces no motion of the vibrator or in other words the vibrator remains stationary, during the time the platen is giving the impression to the sheet but when the impression occurs the roll travels in that part of the groove from b''' to c''' which brings the fistet carriage out from the platen with the fistet on which is the printed sheet returning the carriage while it travels from c''' to a''' with the other fistet carrying the sheet of paper to be printed. Having described the machinery, for producing the impression and change of the fistets from one sett of grooves to the other, together with the situation and arrangement of the several parts in and about the frame, we next proceed to explain that part of the press whose office is to distribute the ink and impact it to the form of type on the bed. In many respects the number of ink rollers and general arrangement of the same are as has been heretofore used but the construction of the ink fountain is varied. Fig. 5. is a representation of different views of the fountain in which is a cross section of the transverse section seen in Fig. 5. a'' is the space for the

the reception of the ink as whole the lower side of the fountain
 roll "B" is immersed. The fountain roller "B" is supported at its
 ends by journals in composition boxes "C" Fig. 10. The boxes are
 placed in a square space adapted to receive them and allow
 sufficient play for the movements back and forth of the ink roller
 against one of the sides of each of the boxes a pin "D" rests
 at other opposite resting against the short arm of a lever "E"
 whose fulcrum is at "F." A screw "G" common to both of the ends
 of the long arms of the levers "E", "E" on being turned presses out
 the long arms of the levers "E", "E" thus causing the fountain roller
 in the boxes "C", "C" to be carried up nearer the edge of the plate
 "H" at pleasure. The springs "H", "H" operating against the pins
 "I", "I" resting against the opposite sides of the boxes "C", "C" and
~~thus~~ when the screw is turned in the other direction cause the
 visiting roller to depart from the edge of the plate "H". The object of
 the above is to regulate the thickness of the surface of the
 ink on the fountain roller. The proper breadth of ink on
 the surface is obtained by a number of screws "L", "L" in the
 side "M"; set at suitable distances apart which when screwed
 up (by their pressure on any particular part of the side "M" of the
 side space) spring that part of it on which they act enough
 to cut off perfectly any portion of ink from adhesion to
 the surface of the fountain roller as it leaves the plate "H".
 The edge of the plate "H" is accurately ground to coincide
 with the edge of the fountain roller in order when necessary
 to shut off the ink perfectly. "O" is the roller for receiving the
 ink from the fountain roller and imparting it to the main dis-
 tributing roller "P". "Q" is the small roller commonly denominated
 also the "lipproller" for lateral distribution. This and the before
 mentioned roller are conical and not similar to others
 heretofore used in printing processes of this description. The main
 cylindrical roller "P" is turned round by a belt or cord pass-
ing over a pulley "R" on its axis and over the small guides justly

pulleys 5.5." over the pulley 6." on the axis of the driving shaft or attached to the arms of the fly wheel. The rollers for applying the ink to the types are 36" x 6" and revolve in bearings attached to the fisher carriage which when it goes out from the forme, carrying a fisher with the printed sheet applies these rollers to the surface of the types passing over the forme twice, when the carriage returns it deposits the rollers on the main distributing cylinder 70" x 12" the above parts of the inking apparatus revolve with the exception of the forme which are consolidated and act similar to those herefore used with only a little variation of form and size to adapt them to the particular shape of the forme of the press and machinery connected to it. ~~N. 11~~ are rollers for supporting the platten on rails N. "N." affixed to or making a part of the frame. Two horizontal shafts 6" x 6" revolve in boxes connected to the platten as seen in the drawings.

On the extremities of each are cranks on which are placed the rolls ~~N. 11~~ During the time the press is in action these cranks with the rolls are turned up on the position in Fig. 8182, but when it becomes necessary to slide the platten away from the forme on the bed they may be turned downwards so that their circumferences shall touch on the tops of the rails N. "N."

A circular plate 10" having two notches opposite to one another is fixed on each shaft. When the rolls ~~N. 11~~ are turned up or down a projection from a spring 12" enters into one of these notches and confines the shaft to the position on which it may be placed. What is usually turned by hand the strength of the suspension is regulated by dividing the circular parts of the nuts on the tops of the bolts 6. 6. into equal distances and counterboring, or drilling, holes at each division into which an index pointer on the end of a spring 2" enters and confines the nut to any position on the screw on which it may be placed. Both nuts are divided alike so that by turning around each the same number of divisional distances "the

the face of the platten will always be parallel to the form of the types in the bed, according as they are turned at pleasure in the most power presses; the "tympan sheet" is moved outward from under the platten with the printed sheet of paper but what I consider a great advantage in my press over others consists in making the tympan sheet stationary. It is stretched over the blanket on the under side of the platten in any convenient manner. When the inference has ceased the platten rises a short distance before the platen begins to ascend in order that the tympan sheet shall effectually clear itself from the paper. This is effected by a proper formation of the cam so that while the roller is moving, over certain part of it it shall produce no motion of the platen. The difficulty generally experienced in other presses consists in the adhesion of the sheet of paper to the tympan sheet so that it becomes necessary that the tympan sheet and the paper be hauled out from between the platten and forms at the same time. By thus raising the platten before the platen the above difficulty is successfully obviated. I have herein above described many improvements in printing press machinery, which I believe to be new and useful. But those to which I shall confine my claims are as follows viz. First. the application of two platen at once, of a form to move in grooves parallel with the face of the types in such manner that on the arrival of either platen at the opposite ends of one set of the grooves it shall be received in grooves in plates of metal moving in a perpendicularly direction to the face of the types and lowered and raised to another set of grooves, either below or above the first, mentioned set of grooves and parallel with the same, to be moved in an opposite direction either in between the plattens and forms or out from the same. Second. The combination of the whole machinery, herein described for producing the above motion of two platen applied to the same side of a form and separate

by and singly. I claim as parts of this combination: The mode of alternately changing a fishet from one set of the grooves to the other set. by grooves in moveable plates α , α' with the construction of the plates as with curved pieces of metal g , g' and springs h , h' to prop the said curved pieces outward and further the small gravitating pieces W , W' and springs X , X' for the object and to act as herein above mentioned. Instead of sets of long grooves X , Y for supporting the ends or projections of the fishets. I substitute long ledges situated in regard to each other as the different sets of grooves above described.

These ledges are also attached to the plates α , α' , on the situation of the grooves in each and being attached to or projecting from the sides at the tops of the curved pieces of metal g , g' . The ends of the fishets are to be made of suitable thickness to have grooves cut or formed in the ends of the same to rest and be sustained on the projections above mentioned. In other respects the action and path described by the motions of the fishets are the same as those aforementioned, but this is a new use new application of the parts or in other words placing the grooves in the ends of the fishets and the projections that move in the grooves on the inside of the frame of the press. This modification of the machinery I claim. Third the combination of the same α with a roller in its end for the purpose of diminishing friction at the time of the impression and also of presenting at every revolution of the case a new surface for the roll in the pattern to move over. Fourth supporting the pattern on a vibrator κ , during its back and forth movements and the motion of a stick $\beta\beta'$, either with or without a roller at κ and to the vibrator to be acted on by a man λ on the main shaft for producing the back and forth movements of the toggles. Fifth. The law it is for constructing the lateral pressure of the lower toggle on the work when the platen be stationary and the top move upwards by the toggles these law may be applied on a

360

ilar manner to the bed for the same purpose of preventing the lateral pressure of the upper toggle on the bed. Sixth the arrangement of a vibrator. It is connected by a joint to one end of a bar A. which is supported at the other end on a pin in the top of a small vibrator B. the said pin having a roller on it travelling in the grooved case C. on the main shaft. for producing the motion of the pitch carriage. Seventh I claim the peculiar arrangement of the several parts for producing the impression as I have above described together with the disposition and adaptation of the the other parts of the machinery to my improvement so as to constitute what is usually denominated a "power press". In testimony that the above is a true specification of my said invention and improvement I have hereunto set my hand the sixteenth day of August in the Year of our Lord Eighteen hundred and thirty four.
